UNITED STATES PATENT OFFICE.

OTIS L. BEARDSLEY, OF CHICAGO, ILLINOIS.

PORTABLE WASHSTAND.

1,187,804.

Specification of Letters Patent. Patented June 20, 1916.

Application filed August 15, 1912. Serial No. 715,207.

To all whom it may concern:

Be it known that I, OTIS L. BEARDSLEY, citizen of the United States, residing at Chicago, in the county of Cook and State of Illinois, have invented a certain new and useful Improvement in Portable Washstands, of which the following is a full, clear, concise, and exact description.

My invention relates to a portable wash-
10 stand, and its object is to provide a wash-
stand which is cheap to manufacture, neat
in appearance, light in weight, durable,
strong and rigid.

My invention contemplates a wash-stand
15 in which the support for the wash-bowl con-
sists of an annular metallic band having an
inturned horizontal flange, said band itself
being supported upon a plurality of legs,
each formed of a wire bent upon itself and
20 twisted for a long portion of its length, the
ends of the wire being secured upon the in-
side of said metallic band and the several
legs being suitably braced intermediate their
ends to prevent their spreading apart.

25 My invention may be more readily under-
stood by reference to the accompanying
drawings, in which—

Figure 1 is a perspective view of a wash-
30 stand embodying my invention; Fig. 2 is an
enlarged, fragmentary, vertical section of
the annular supporting band and the wash-
bowl held therein; and Fig. 3 is an enlarged,
fragmentary, vertical section of the shelf
which constitutes a brace for the legs.

35 Similar letters of reference refer to simi-
lar parts throughout the several views.

Referring to the drawings, 1 is an annu-
lar, metallic band having an inturned hori-
zontal flange 2 upon which rests the rim of
40 the wash-bowl 3.

The band 1 is supported by a plurality of
legs 4 each consisting of a wire bent upon
itself and provided with a loop 5 constitut-
ing the foot, each of said wires being twisted
45 together for a portion of its length as at 6
and the upper ends of said wires being drawn
apart and the separated ends secured as at
7 upon the inside of the metallic band by
means of bolts or rivets 8, or in other suitable
50 manner.

The legs 4 are braced intermediate their
lengths, such brace preferably consisting of
a circular metallic shelf 9 formed of sheet
metal having a depending circumferential
flange 10 against which the legs are clamped
55 by bolts 11. The shelf 9 has a concave up-
per surface 13, whereby water that may be
spilt from a pitcher 12, supported upon said
shelf, may be prevented from running over
on the floor. Such shelf though formed of
60 sheet metal is, by reason of its concave shape
and the circumferential flange, very stiff and
forms a rigid brace for said legs. However,
if desired, additional cross braces 14 may be
employed for bracing said legs.

The portable wash-stand of my invention
is preferably provided with a soap-holder
15 riveted to the band 1 and a towel rack 16,
the latter consisting of a curved wire secured
at its end to the band 1.

It will be noted that the wash-stand of my
invention is formed wholly of metal, and
may be readily cleansed, thus being sanitary.
The inturned flange 2, in addition to forming
a suitable support for the wash-bowl, serves
70 to hold the outer surface of the bowl from
coming in contact with the inner ends of the
bolts 8, which might otherwise mar the ex-
terior surface of the bowl. Said flange 2
also materially strengthens said band 1 and
80 at the same time adds to the attractive ap-
pearance of the wash-stand. The above de-
scribed shape of the shelf 9 adds both to its
strength and the attractiveness of its appear-
ance. The concavity upon its upper surface,
85 while it effectively serves as a catch bowl for
water that may slop over from the pitcher,
can readily be dried or cleansed, and pos-
sesses no sharp corners which might collect
dirt.

90 What I claim is:

A portable wash-stand comprising an
angle iron formed as a closed ring, a plu-
rality of legs each consisting of a wire dou-
bled on itself with the lower ends of the two
strands twisted together and the upper ends
95 spaced apart and secured inside the vertical
flange of said angle iron, the latter serving to
support a wash-bowl substantially equal in
diameter to said ring and fitting within and
100

resting on the horizontal flange of said angle iron, whereby said wash-bowl is equally accessible from all sides of the supporting stand, and a metal shelf secured to said legs 5 and serving to brace and reinforce the structure, said shelf being slightly concave upon its upper side to catch drip water from said bowl and being adapted to support a pitcher,

with the latter also accessible from all sides of said stand.

In witness whereof, I hereunto subscribe my name this 29th day of July, A. D., 1912.

OTIS L. BEARDSLEY.
